(57) **CLAIM**

The ornamental design for an arm for lighting fixture, as shown and described.

DESCRIPTION

FIG. 1 is a right side view of an arm for lighting fixture.

FIG. 2 is a left side view of an arm for lighting fixture.

FIG. 3 is a back view of an arm for lighting fixture.

FIG. 4 is a front view of an arm for lighting fixture.

FIG. 5 is a top view of an arm for lighting fixture; and,

FIG. 6 is a bottom view of an arm for lighting fixture.

Those portions of the drawing shown in dashed lines are for illustrative purposes only, and do not form a part of the inventive design.
